COMBINATION COUCH AND BED
STRUCTURE

Lake C. Johnson, Pasadena, Calif.

Application June 11, 1941, Serial No. 397,576

4 Claims. (Cl. 5—47)

This invention relates to convertible furniture and particularly pertains to a trolley hinge.

Various types of convertible furniture are now being made which are intended to serve the purpose of a couch and a bed. These structures are so designed as to provide a base having the dimensions of an ordinary couch with seat and back sections articulately connected to each other and the base, whereby these sections may be disposed with the back portion in an upright position when the article of furniture is used for a couch and with the back and seat disposed in a common horizontal plane when a bed is desired. The articulate connection between the base, back and seat portions is known to the trade as a trolley hinge. In the operation of these devices it is necessary to lift and shift the seat portion and thereafter move the seat and back portions into alignment. This operation is laborious due to the weight of the back and seat portions, and it is the principal object of the present invention to provide a trolley hinge structure in which the various weighted parts are counterbalanced with spring means associated with the trolley hinge and included in the trolley hinge unit, whereby the back and seat portions may be moved to and from their different positions with ease, and may be temporarily latched in either of their extreme positions.

The present invention contemplates provision of a base carrying pivotal links upon which hinge brackets of a couch seat and back are pivotally secured, said brackets being fitted with latch means whereby they may be disposed in locked and released positions, the brackets and links carrying spring counterbalance members tending to yieldably assist movement of the elements and to thus partially support the load imposed by the weight of the back portion and the seat portion as they move to their various positions.

The invention is illustrated by way of example in the accompanying drawings in which:

Figure 1 is a view in side elevation showing the normal position of the couch with the back in its substantially vertical position.

Fig. 2 is a view showing the couch in an intermediate position with the back disposed horizontally.

Fig. 3 is a view showing the back and seat sections disposed in horizontal alignment to form the bed.

Fig. 4 is a view similar to Fig. 1 but showing the opposite side of the structure to more clearly disclose the relationship of the supporting links,

and also indicates the balanced intermediate position of the back and seat in dotted lines.

Fig. 5 is an enlarged fragmentary view indicating the tripping action of the lock means when the lock structure is in the intermediate position shown in Fig. 2.

Fig. 6 is a view in transverse section as seen on the line 6—6 of Fig. 2 showing the pin lock.

Fig. 7 is a view in vertical section as seen on the line 7—7 of Fig. 3 and shows details of the hinge construction.

Referring more particularly to the drawings, 10 indicates a base structure. This structure includes the usual rectangular frame having front 15 and rear rails 11 and 12 and opposite end rails 13. In Figures 1 to 4 of the drawings it is to be understood that the base structure and the cushion arrangement are indicated generally, and that the details of cushioning and uphol- 20 stering the various parts are not involved in the present invention. Mounted upon opposite ends 13 of the base frame are fastening brackets 14 and 15. The bracket 14 is disposed substantially in vertical alignment below a back section 16 25 and is fitted with a pivot pin 17. This pivot pin extends horizontally and is pivotally connected to a link 18 which when the back is in its normal vertical position will stand substantially vertically. The bracket 15 is fitted with a pivot pin 19 and is pivotally connected to a link 20. The link 20 extends upwardly beneath a seat section 21 and is disposed at an angle to the general position of the link 18 when the link 18 is 30 vertical. The back section 16 has a rigid frame structure 22 to which a hinge bracket 23 is secured. This hinge bracket extends substantially horizontally when the back section is in its normal position and with the back section inclined normally. The upper end of the link 18 is 35 pivotally secured to the hinge bracket 23 by a pivot pin 24. The hinge bracket may be generally considered as being triangular. At the outer point thereof a pintle pin 25 is secured and passes through an opening in the upper end 40 of the link 20. This pin also passes through an opening in the upper end of a hinge bracket 26 which is secured to the frame structure 27 of the seat section 21. By this arrangement the pintle pin 25 secures the hinge brackets 23 and 26 in pivotal connection, and also insures that the pivotal axis of the hinge brackets 23 and 26 and the pivotal connection of the link 20 are coincident. It will thus be seen that the hinge brackets 23 and 26 are hinged together by the 45 pivot pin 25 and that the links 18 and 20 di-

rectly support the back section 16 and the seat section 21 through the medium of said brackets. The brackets 23 and 26 are fitted with bolting flanges 28 and 29 by which the brackets may be bolted to the frame structures 22 and 21, respectively, of the back and seat. Attention is directed to the fact that at all times the link pivots 17 and 19 will be fixed relative to the base, and that the pivots 24 and 25 securing the links 18 and 20 to the hinge structure will always be spaced closer together than the spacing of pivots 17 and 19. This is for the purpose of counterbalancing the back and seat portions and holding them in extreme positions, as will be hereinafter explained. It is also to be pointed out that the base is formed with a recess 13' in the upper face of each of the end rails 13 to receive the seat frame 21, and that the inner edge of this frame will abut against a shoulder 27' when the back and seat are in their normal position, and that the pintle pin 25 of the hinge and link 20 will have passed over the axis of the pivot pin 19. Thus, the back and seat will rest firmly in position until positively moved.

As shown in Fig. 1 of the drawings, the back element is maintained in its upright position with relation to the seat element by a latch bar 30 which is pivotally connected to the hinge bracket 26 adjacent to its lower edge by a pivot pin 31. An outturned extension 32 is formed on the end of the latch bar adjacent to the pin 31. This extension has an opening 33 through it to receive one leg of a U-spring 34. The opposite leg of the U-spring 34 lies against the bolting flange 29 of the bracket 26 and tends to urge the free end of the latch bar 30 toward its lowermost position. The free end of the latch bar 30 is formed with a latch notch 35 along its lower edge. A latch pin 36' and keeper 36 are carried by the hinge bracket 23. This keeper is substantially U-shaped so that the free end of the latch bar 30 may move longitudinally through it as it moves from a latched to an unlatched position, or vice versa. Carried upon the free end of the lock bar 30 is a latch detent 37 which is pivoted to the bar at 38. This detent is fitted with a shoulder 39 so that when it is desired to release the lock bar the detent will hold the latch notch 35 away from the member 36' and permit the hinge bracket 26 and the seat section 21 to swing downwardly to the position indicated in Fig. 3 of the drawings.

As previously pointed out, the trolley hinges comprising brackets 23 and 26 are designed to support the weight of the back section 16 and the seat section 21 in their different positions while shifting with relation to the base 10 or while being moved with relation to each other to and from the positions indicated in Figs. 1, 2, 3 and 4. The resistance to the shifting movement of the back and seat sections is to an extent counterbalanced by a spring 40 which is of the helical type and is formed with hooks 41 and 42 at its opposite ends. The hook 41 engages an eye in a lever extension 43 secured to the link 20 and is disposed at right angles to the link 20 and positioned adjacent to the pivot 19. The hook at the opposite end of the spring 40 engages an eye in a lever extension 44. This lever extension is carried by the link 18 and is disposed substantially at an acute angle thereto. It will be seen from an examination of the dotted line showing in Fig. 4 of the drawings that at the time the links 18 and 20 are in position to support the back

and seat sections at an intermediate balanced position with the seat section and the back section at angles to the vertical that the lever extensions 43 and 44 are substantially in horizontal alignment with their eyes at the shortest distance between each other. This makes it easy to shift the back and seat in either direction and insures that as the back and seat are moved toward and away from their intermediate position shown by dotted lines in Fig. 4, the spring 40 will counterbalance the parts. Attention is directed to Figs. 1 and 2 of the drawings, where it will be seen that in normal position of the back and seat the link 18 is substantially on dead center, and the link 20 has swung a considerable distance over its pivot pin 19. In the dotted line position indicated in Fig. 4 the weight of the back and seat is directly supported on link 20 while these parts move from the position indicated in Fig. 1 to the position indicated in Fig. 3. This insures that when the back and seat sections move toward positions at either side of this centered and balanced position the spring 40 will tend to counterbalance the weight of the back and seat. It is to be understood that while the spring 40 is shown connected to the members 43 and 44 that separate springs might be used. In order to balance the weight of the back and the seat with relation to the action of spring 40 it is evident that the eyes in the levers 43 and 44 may be spaced to obtain the proper leverage action. It will be seen in Figs. 2 and 3 that in these positions the lever extensions 43 and 44 are at their greatest distance from each other so that the spring 40 will at this time be under extreme tension, and so that when the parts are manipulated to restore the back section 16 to a substantially vertical position and the seat section to its original horizontal position the spring 40 will tend to contract and aid in counterbalancing the load and shifting the parts from the balanced position.

In addition to the counterbalancing action provided by the spring 40 the hinge brackets 23 and 26 are provided with a counterbalanced spring 45. This spring is of the coil and hairpin type; that is to say it has a central coil 46 represented by a plurality of convolutions arranged in helical shape, the opposite ends of the spring terminating in legs 47 and 48. The leg 47 is fixed to the hinge bracket 23 upon a bolt or pin 49 adjacent to the lower edge of the bracket when considered in its normal position with the back disposed substantially vertically. The leg 48 is secured by a bolt or pin 50 carried by the bracket 26 along the edge contiguous to the bracket 23. Thus when the hinge brackets swing toward each other the spring legs 47 and 48 will swing toward each other and the convolutions of the coil portion 46 will be coiled as resistance is given to the movement of the hinge brackets 23 and 26 toward each other, and will tend to recoil and swing the hinge brackets 23 and 26 to their outermost positions while counterbalancing the weight of the seat section as it thus moves.

The spring 45 is of greater strength than represented by the weight of the back and seat sections. Thus when the seat and back are horizontal there is a tendency for the back section to lift and to swing on the pivot pin 25. In order to hold the seat and back in rigid relation to each other when horizontally disposed, as indicated in Fig. 3 of the drawings, it is desirable to provide a hinge lock generally indicated at 55 in Fig. 6 of the drawings. This lock comprises a recipro-

cating pin 56 extending through the leaf of the hinge bracket 23 and formed with an enlarged conical head 57 which occurs between the leaf and the lock bar 30. The lock bar is formed with an opening 58 through which the head 57 of the pin will partially extend and by which the pin may be moved in the direction of said opening by a spring 59. When the back has been swung downwardly to its position of horizontal alignment with the base, the hinge bracket 23 will bear such a relation to the link 20 as to cause a notch 60 to register with the end of the pin 56 so that the pin will slide into the notch and temporarily hold the back down against the action of the spring 45, which tends to spread the legs 47 and 48 of the spring and swing the seat and back into angular relation to each other.

In operation of the present invention a base structure 10 is provided to which the links 18 and 20 are pivotally secured by brackets 14 and 15. The back section 16 and the seat section 21 are constructed as desired and secured in their assembled position by hinge brackets 23 and 26. It is to be understood in this description that while one mounting unit is shown in the drawing including the hinge brackets and the links, that it is necessary to provide one complete unit of this type for each end of the back and seat sections with the exception, however, that in the event springs 40 and 46 are only needed at one end to counterbalance the weight they may be used. Assuming that in the initial position the back section 16 and the seat section 21 are shown as in Fig. 1, the hinge brackets 23 and 26 will be swung with relation to each other substantially to their extreme position of separation. The brackets will be locked in this position by the lock bar 30, the notch 35 of which engages the pin of the member 36 and holds the back section in its substantially vertical position, as shown in Fig. 1. When it is desired to convert the structure from a couch to a bed the forward edge of the couch is swung upwardly. As this takes place the back section 16 will swing downwardly while the seat and back sections remain in their original positions with relation to each other as held by the lock bar 30. Movement from this position will be assisted by the spring 40 which tends to hold the links 18 and 20 in the position shown by dotted lines in Fig. 4 of the drawings. As the seat section 21 is swung upwardly it will shift forwardly on the links 18 and 20 and the back section 16 will swing downwardly, so that these sections will assume the position shown in Fig. 2 of the drawings. After the back section has come to rest in a horizontal position the seat section is tilted upwardly and rearwardly a short distance farther. This will pull the notch 35 of the lock bar 30 forwardly with relation to pin 36' and will permit the shoulder 39 of the detent 37 to pass over and to engage the lock pin portion 36' of the member 36. As the seat is slightly lowered the detent 37 will act to lift the free end of the lock bar 30 so that the groove 35 will ride over the pin 36'. The seat is then free and is lowered forwardly and downwardly as it swings on the pivot pin 25 of the hinge brackets 23 and 26. It is to be understood that while the lock bar 30 has held the hinge brackets 23 and 26 in their latched position as disposed at an angle to each other, the head 57 of pin 56 seats within the opening 58 in the lock bar 30, and the pin is retracted from the plane of travel within which the link 20 moves. The latch structure of the

lock bar 30 is so designed as to release the lock bar by the action of the detent 37 at a point when the pin 56 is in register with the notch 60 in the link 20. When the lock bar 30 and the groove 35 move relative to pin 36', as well as when the lock bar is released by the action of the detent 37, the bar 30 moves the opening 58 out of register with the head 57 of the lock pin. This moves the lock pin 56 into the notch 60 on link 20 and as the bar 30 moves with the seat section continues to bear against the head 57 and hold the pin 56 in the notch 60. Then any tendency for the back section 16 to rise or for the two sections to pivot on the axis 25 of the hinge brackets will be eliminated. Thus the seat and back will assume horizontally aligned positions for the purpose of making a bed, and the back section will be locked in this position. As shown in Fig. 3 of the drawings, the movement of the seat to a position of horizontal alignment with the back 16 will cause the hinge brackets 23 and 26 to swing towards each other around the pivot 25 while forcing the legs 47 and 48 of the spring 45 together so that they will assume the position indicated in Fig. 3 of the drawings. It will be evident that this action of the spring 45 will tend to cushion the downward movement of the seat section, and that when the structure is again restored to its normal position to perform the functions of a couch this spring will aid in supporting the weight of the seat section.

When it is desired to restore the back and seat sections 16 and 21 to their original positions forming a couch the forward edge of the seat section is elevated to substantially the position shown in Fig. 2 of the drawings. The spring 34 will tend to urge the lock bar downwardly as it is drawn through the member 36, and thus the pin 36' of element 36 will engage the shoulder of the latch notch 35 and hold the hinge bracket sections 23 and 26 in the positions where the back section 16 and the seat section 21 will be angularly disposed as shown in Fig. 2. As the seat section 23 is swung upwardly to the position indicated in Fig. 2 of the drawings it will be evident that the end of the head 57 of the pin 56 will be bearing against the side face of the lock bar 30. When the notch 35 of the lock bar comes to register with the pin of the element 36 the opening 58 in the lock bar 30 will be in exact register with the head 57 of the pin. This will permit the head of the pin to move into the hole 58 while the opposite end of the pin is retracted from engagement with the notch 60 in the link 20. This will unlatch the link 20 with relation to the bracket of the back section and will permit the bracket 23 to swing upwardly around the hinge pin 25 and for the links 18 and 20 to swing upon their pivots 17 and 19 from the position shown in Fig. 2 to the position shown in Fig. 1. It will be seen that during this motion the links 18 and 20 shift the assembled back and seat sections from a foremost position, as shown in Figs. 2 and 3, to a rearmost position as shown in Fig. 1. This also would cause the back section to move outwardly from the wall on the forward shift and to move rearwardly and upwardly to a position in close proximity to the wall when the shift is made to the position shown in Fig. 1. It is to be understood that after the seat section 21 has been swung upwardly to the position shown in Fig. 2 and the lock bar 30 has engaged the pin of the member 36 the structure is ready to be restored to its position as a couch. Slight downward pres-

sure is then applied to the forward edge of the seat section so that the seat and back sections will shift together upon the links 18 and 20 to the original position indicated in Fig. 1. The spring 40, which is under tension while the back and seat sections assume horizontal positions or when the back and seat are in a couch position, will contract at the intermediate position indicated by dotted lines in Fig. 4 and will aid in supporting the weight and in shifting the sections toward their extreme positions. It will also be evident that due to the arrangement of the links 18 and 20 and the angular disposition of their lever arms 43 and 44, the spring 40 will tend to maintain the back and seat sections in the position indicated by dotted lines in Fig. 4 of the drawings and to counterbalance them as they move in either position therefrom.

It will thus be seen that the trolley hinge structure here shown discloses simple and effective means, whereby the back section and the seat section of a couch may be disposed in positions to serve as a couch or bed, and that the weight of the parts will be counterbalanced during transition of the parts from one position to the other.

It will further be evident that the structure here shown provides automatic means for locking the hinge when the seat and back parts are in their horizontally aligned position so that there will be no possibility for the structure to fold together accidentally, the structure further acting to automatically release when a normal operation takes place to manipulate the seat so that the seat and back sections may move to their original positions forming a couch.

While I have shown the preferred form of my invention as now known to me, it will be understood that various changes may be made in combination, construction, and arrangements of parts by those skilled in the art without departing from the spirit of my invention as claimed.

Having thus described my invention, what I claim and desire to secure by Letters Patent is:

1. A combination couch and bed, comprising a horizontal base structure, a seat section normally resting thereupon, a back structure disposed substantially vertically at the rear edge of the seat structure, hinges articulately connecting the contiguous edges of the back structure and the seat structure, a latch engaging a hinge to hold the back and seat structures in their normal positions and to permit the back and seat structures to swing to horizontally aligned positions, a pair of links for each hinge structure, one of said links being pivotally connected to the hinge leaf of the back section and extending downwardly and vertically to be pivotally fixed to the base when the back section is in its substantially vertical position, the other of said links being pivoted on the pintle pin of the hinge, said links acting to shift the hinge structure forwardly from a folded position through an intermediate position to an unfolded position, the lower end extending

downwardly and forwardly and being pivoted to the base, lever arms, one rigidly secured to the first named link and the other rigidly secured to the second named link, said lever arms projecting toward each other and lying in substantially the same plane when the back section and the seat section are at a balanced intermediate position, and a spring yieldably connecting the free ends of the two link levers and tending to act to cushion the weight of the seat and back sections as they swing from their intermediate balanced position.

2. The structure of claim 1 together with lock means cooperating with one of said links and acting to maintain the back section horizontal while permitting free swinging movement of the seat section to a horizontal position when the latch is released.

3. The structure of claim 1 together with lock means cooperating with one of said links and acting to maintain the back section horizontal while permitting free swinging movement of the seat section to a horizontal position when the latch is released, and a spring disposed between the leaves of the hinge and being placed under compression when the leaves are moved to their closed position and the back and seat sections are horizontally disposed, whereby said spring will tend to counterbalance the weight of the seat section as it is swung toward and away from its position of horizontal alignment with the back section.

4. A combined couch and bed, comprising a horizontal base structure, a seat section normally resting thereon, a back section disposed substantially vertical at the rear edge of the seat section, hinge brackets, one secured to each of said sections at contiguous edges thereof, a pintle pin connecting complementary brackets, yieldable means associated with said brackets and tending to urge them to a folded position as assumed when the seat and back sections form a couch, a link engaging the pintle pin at its upper end and being pivotally mounted on the base at its lower end, said last named pivot being in advance of the position of the pintle pin when a couch is being formed, a link pivoted at its upper end to the hinge bracket carried by the back section, a fixed pivot carried by the base and upon which the lower end of said link is mounted, said link standing substantially vertical when the structure forms a couch, lever arms, one formed rigidly with each of said links and being directed toward each other, and a tension spring connecting said lever arms, the arms being in spaced parallel planes when the hinge structure is in either of its extreme positions, whereby to impose tension upon the spring and lying in a common plane when the structure is in its intermediate position whereby the distance between the free ends of the arms will be shortened and tension on the spring relieved.

LAKE C. JOHNSON.
